UNITED STATES PATENT OFFICE

ORON N. PHILLIPS, OF REYNOLDS, ILLINOIS

FUEL SUPPLY SYSTEM

Application filed February 27, 1930. Serial No. 431,883.

This invention aims to provide a fuel supply system for an internal combustion engine which will afford a smooth pressure at all times, the fuel being furnished at a pressure which increases with the velocity of the motor until a maximum degree. Another object of the invention is to provide a fuel supply system which is not dependent upon gravity, the proper amount of fuel being pumped 10 into the motor at any speed.

It is within the province of the disclosure to improve generally and to enhance the utility of devices of that type to which the present invention appertains.

With the foregoing and other objects in view, which will appear as the description proceeds, the invention resides in the combination and arrangement of parts and in the details of construction hereinafter described and claimed, it being understood that changes may be made in the precise embodiment of the invention herein disclosed, within the scope of what is claimed, without departing from the spirit of the invention.

In the drawings:

Figure 1 shows in elevation, a system constructed in accordance with the invention, parts being broken away, and parts being in section;

Figure 2 is a sectional view showing the nozzle and attendant parts;

Figure 3 is a sectional detail of the vent valve;

Figure 4 is a vertical section disclosing the valve which maintains a constant level in the tank;

Figure 5 is a plan of the valve base of Figure 4;

Figure 6 is a plan showing part of the valve mechanism at the top of the main fuel tank;

Figure 7 is a section of the valve at the top of the main fuel tank.

The numeral 1 marks the main fuel supply tank for an internal combustion engine used in connection with an aeroplane, auto, or other instrumentality that requires a motor of the sort alluded to. At 2, there appears a pump which is driven, preferably, by the cam shaft 3 of the engine 4. An auxiliary tank, or filter tank, is supported at 6 in any

convenient place, the tank 5 often being placed under the hood, in an automobile. The dashboard of the automobile is shown at 7.

Referring to Figure 1, in comparison with Figure 4, it will be seen that a float valve mechanism 8 is located on the bottom of the main fuel tank 1. The float valve mechanism 8 embodies a base 9 having outstanding lugs 10 on its edge. The base 9 is supplied with upstanding guides 11 surrounding a passage 12 which extends downwardly through a reduced neck 14 on the base 9. The neck 14 projects through a hole 15 in the bottom of the tank 1, and a nut 16 is threaded on the neck, to afford a tight joint, and to hold the float valve mechanism 8 in place, the bottom of the tank 1 being bound hermetically between the base 9 and the nut 16. A pipe 17 leads from the neck 14 to the pump 2, which, preferably, is of the sort shown in my co-pending application, Serial No. 441,618, filed April 4, 1930.

The float valve mechanism 8 embodies a casing 18 having bayonet slots 19 adapted to receive the lugs 10 on the base 9, a secure but releasable connection between the parts 9 and 18 thus being afforded. The casing 18 has longitudinal openings 20 and is surrounded by a fine-mesh screen 21. A float 22 is mounted for reciprocation in the casing 18 and substantially fills the casing, so far as cross section is concerned. The float 22 has an upper stem 23 which is guided in an aperture 24 in the top of the casing 18. The float 22 is supplied with a lower stem 25 carrying a valve 26 mounted to slide within the guides 11 of the base 9. The valve 26 has a tapered end 27 which seats on the base 9 at the upper end of the passage 12.

A check valve mechanism 28 is mounted on the top of the main fuel tank 1, as shown in Figure 1, the check valve mechanism possessing sundry details of structure which have been made the subject of illustration in Figures 6 and 7.

The check valve mechanism 28 comprises a foot 29, in the form of a plate, having a cavity 30 in its bottom, the foot 29 being secured to the top of the tank 1, with the cavity

30 in registration with a hole 31 in the top of the tank. The foot 29 has a reduced body 32 terminating in a reduced head 33.

5 A cap 34 is threaded on the body 32 and there is a chamber 35 in the cap. In the head 33 and the body 32 is a double-diameter bore 36 defining a shoulder or valve seat 37. The body 32 is supplied with a lateral inlet 38 communicating with the bore 36. A plurality of passages 39 are formed in the head 33 and the body 32, around the bore 36, the passages communicating at their lower ends with the cavity 30, and at their upper ends with the chamber 35 within the cap 34. A check valve, for instance, a ball 40, rests on the seat 37 under the compulsion of a compression spring 41 bearing at its upper end against the cap 34, and at its lower end against the valve 40. By means of a 10 coupling 42, one end of a pipe 43 is held in the inlet 38, and by means of a nut 44, the opposite end of the pipe is held to an elbow 45 which is in communication with the tank 5 through the top of the tank, the elbow 45 being external to a filter bag 46 carried by the top of the tank 5; the filter bag preferably being made of chamois skin.

15 In Figure 2, it appears that a nozzle 47 is seated removably in the horizontal portion 30 of the elbow 45, the nozzle having a bore 48, and being provided with a foot 49 that bears against the end of the nozzle 45. The pipe 43 is flared at 50 to fit against the foot 49 of the nozzle 47, or against the end of the nozzle 45, and the parts specified are held together by a packing 51 (metallic or otherwise) within the nut 44 and engaged by the end wall 52 of the nut.

20 A pipe 53 is connected at one end to the pump 2, and is connected at the opposite end to an elbow 54 mounted in the top of the tank 5 and discharging into the filter bag 46, hereinbefore mentioned.

25 A vent pipe 55 is provided and may be of approximately rectangular form, one end of the vent pipe communicating with the tank 5 through the top of the tank, and the other end of the pipe projecting toward the dashboard 7. There is a cap 56 on the horizontal end of the pipe 55, and the pipe 55 has a slide opening 57 located closely adjacent to the cap 56, the opening 57 being under the governance of a valve 58 threaded in the cap 56 and journaled in the dashboard 7, the valve 58 being supplied with a turning button 59 disposed within convenient reach of the driver of the vehicle, to the rear of the dashboard 7.

30 A pipe 60 may lead from the bottom of the auxiliary tank 5 to a pressure gage (not shown), the pipe 61 that leads to the carburetor, (not shown) being connected to the bottom of the tank 5.

35 The pipe 53 is connected to the pump 2

by a check valve 62 that closes toward the pump.

30 In practical operation, the supply line from the tank 1 to the carburetor (not shown) includes the pipe 17, the suction and force pump 2, the pipe 53, the elbow 54, the filter bag 46, the auxiliary tank 5, and the pipe 61. The fuel has to pass through the filter bag 46, and impurities in the fuel will be retained 70 in the filter bag. The fuel goes forward to the carburetor under adequate and constant pressure. The fuel is kept clean and free from moisture because it is filtered through the chamois bag 46 under pressure. The filter bag can be removed and cleaned, upon 75 occasion. The auxiliary tank 5, which encloses the filter bag 46, serves as a supply tank for the carburetor, storing up fuel which frequently leaks from the carburetor. The tank 5 insures a sufficient quantity of gasoline in 80 the carburetor bowl at all times. The check valve 62 prevents fuel from returning to the pump 2 from the auxiliary tank 5, and also aids in preventing the return of fuel to the tank 1 from the pump when the system is not 85 working.

90 The excess fuel flows through the elbow 45, the pipe 43, and the check valve mechanism 28 to the main tank 1. The cartridge-like nozzle 47 may be easily and quickly mounted in place, it being possible to substitute one nozzle for another, the bores 48 of the nozzles being different. In this way, the amount of fuel going back to the main tank 1 through the pipe 43 can be regulated, and 95 the exact pressure to the carburetor through the pipe 61 can be attained.

100 The valve 58 can be manipulated by means of the button 59 to break the partial vacuum in the auxiliary tank 5. Because the heat of the motor evaporates the more volatile part 105 of the fuel, it is of prime importance to allow fresh fuel to flow into the carburetor in cold weather, to facilitate starting, or when the carburetor is dry, after standing idle for a 110 long time. By manipulating the valve 58 until the vent 57 of Figure 3 is opened, a fresh supply of fuel is permitted to flow from the tank 5 to the carburetor, as and for the purpose specified.

115 When the fuel falls to a predetermined level in the tank 1, the float 22 moved downwardly, and the valve 26 closes, the flow of fuel through the pipe 17 being stopped, and the engine 4 ceasing immediately to operate. 120 In view of the provision of the mechanism of Figure 4, especially in conjunction with the check valve of Figure 7, the auxiliary tank 5 and all of the various pipes remain full, and are never sucked dry of fuel, as 125 takes place in ordinary mechanisms, when the fuel is permitted to be depleted completely.

130 As to the operation of the specific check valve of Figures 7 and 6, the fuel enters by

the inlet 38, traverses the bore 36, enters the chamber 35, after having raised the check valve 40, and moves downwardly through the passages 35 into the chamber 30, and thence through the hole 31, into the tank 1.

5 The fuel inlet pipe 53, the second or over-flow pipe 43, and the pipe 17, form a loop-shaped conduit, in which the main fuel tank 1 and the force pump 2 are interposed, the 10 auxiliary or filter tank 5 being interposed in the said conduit, and being located between the outlet side of the pump and the inlet of the main tank 1. The pipe 61 may be referred to as a third pipe, and the nozzle 47 15 may be denominated a reducer.

Having thus described the invention, what is claimed is:—

In a device of the class described, a loop-shaped conduit, a main liquid tank interposed in the conduit, a force pump interposed in the conduit, an auxiliary tank interposed in the conduit and located between the outlet side of the pump and the inlet of the main tank, an outlet for the auxiliary tank, 20 a vent for the auxiliary tank, a valve positively closing the vent to permit the pump to maintain an even pressure, and means under the control of an operator for opening the valve, to procure a flow through the outlet 25 when the pump is stopped.

In testimony that I claim the foregoing as my own, I have hereto affixed my signature.

ORON N. PHILLIPS.
